United States Patent Office.

GEORGE H. SHEARER, OF BAY CITY, MICHIGAN.

Letters Patent No. 94,919, dated September 14, 1869.

IMPROVEMENT IN SAW-MILLS.

The Schedule referred to in these Letters Patent and making part of the same.

To all whom it may concern:

Be it known that I, GEORGE H. SHEARER, of Bay City, in the county of Bay, and State of Michigan, have invented certain new and useful Improvements in Saw-Mills, of which the following is a full, clear, and exact description, reference being had to the accompanying drawing, making part of this specification, in which—

Figure 1 is a front view of my improvement;

Figure 2 is a rear view of the same;

Figure 3 is a side or edge view of the same; and

Figure 4 is a detached view of the removable part of the jamb or fender, and also of the mortise into which it is fitted.

Similar letters of reference indicate similar parts in all the figures.

The invention consists of a novel construction of the jambs or fender-posts of a saw-mill, whereby ready access may be had to the bearing-blocks of noddle-pins or cross-heads, for the purpose of adjusting or replacing them, as will be readily understood from the following description.

A represents an aperture or mortise, extending entirely through the jamb, at a point traversed by the cross-head or slide.

B is a cap, provided with a tenon, fitting closely to the mortise A, and of such length that it will just reach through the jamb, forming a smooth, or nearly smooth surface upon its inner side.

This cap or block is secured in its place by means of the bar F, which passes through the perforated

ears f f, or by the pivoted latch E, which engages with the catches e e.

The ways in which cross-heads or guides move are composed of the sides C C and back D, all properly secured to the jambs.

The edges of the back D are bevelled to fit corresponding rebates upon the inner angles of the sides C C, and may be easily withdrawn by sliding them out endwise, first removing the bolts or screws at each end.

From the foregoing description, it will be seen that, by removing the back D and cap B, the bearing-blocks in the ends of the noddle-pin or cross-head may be reached without disturbing the working-parts of the mill.

Having thus described my improvement,

What I claim as new, and wish to secure by Letters Patent, is—

1. The construction of the jambs or ways, or both, of a saw-mill, in such manner that access may be had to the bearing-ends of the noddle-pin or cross-head without removing or loosening said noddle, or either side of the ways in which it moves.

2. The jambs or ways of a saw-mill, provided with mortises or perforations, for the purpose set forth.

3. The removable back D, in combination with the sides C C, operating as set forth.

4. The cap B, in combination with the jamb A.

Witnesses: GEORGE H. SHEARER.

THOS. MUNN,
THOMAS FOX.
